Specification for Design.

Patented Nov. 1, 1921.

Application filed April 24, 1920. Serial No. 376,417. Term of patent 3½ years.

To all whom it may concern:

Be it known that I, JOHN MACQUARRIE, a citizen of the United States, and a resident of the city and county of San Francisco, in the State of California, have invented a new, original, and ornamental Design for Statuettes, of which the following is a specification, reference being had to the accompanying drawing, forming a part thereof.

Fig. 2 is a three-quarter back view thereof.

I claim:

The ornamental design for a statuette as shown.

JOHN MACQUARRIE.
